UNITED STATES PATENT OFFICE.

NELSON BARNUM, OF ST. LOUIS, MISSOURI.

SASH-FASTENER.

Specification of Letters Patent No. 26,405, dated December 13, 1859.

To all whom it may concern:

Be it known that I, NELSON BARNUM, of the city and county of St. Louis and State of Missouri, have invented a new and useful Improvement in Sash Supporters and Locks; and I do hereby declare that the following is a full, clear, and exact description of the same, reference being had to the annexed drawing, making part of this specification, in which—

10 Figure 1 is a side elevation; Fig. 2, a longitudinal section, and Fig. 3 is also a longitudinal section upon an enlarged scale.

15 The nature and object of my invention will be understood from the following description.

Similar letters of reference represent corresponding parts of the different figures of the drawing annexed.

20 Upon the drawing, A represents the side stile of the frame or sash, and through the edge of this stile a groove is cut in the longitudinal direction, as shown at D, and into this groove a strip B is introduced, which is prevented from slipping endwise by means 25 of the screws K K, and behind this strip springs C C are introduced for the purpose of pressing the strip hard against the side of the window frame. The object of this strip B with the springs C C behind it is to hold the sash in any given position by the friction induced by the springs.

Now to lock the sash when it is down and to facilitate the raising and lowering thereof 35 I introduce the bolt I in the strip B and operate it by means of the lever H, which is attached to it by means of the rod G and the spring J, the bolt being thrown back by means of the lever and forward by the 40 spring J, the one end of which is secured in the strip in the manner shown. Besides the

locking and unlocking of the sash, the lever H and rod G perform the additional function of compressing the springs C C by drawing back the strip B, which thus diminishes the friction and allows the sash to move up and down with facility, and to keep the rod G and lever H always in the position shown when the sash is at rest. The spring E is placed around the inside end of the rod as shown, so as to have its bearing against the bottom of the groove D, and the inside head of the rod. The operation of this contrivance is as follows: When it is desired to raise or lower the sash, the lever H (which is hinged to the sash at r) is depressed, which draws the spring J back to the bottom of the groove in which it operates, and then by a still further compression of the lever the strip B is drawn back in the groove D, which releases the sash and allows it to move with ease; and that the sash may be made to expand to an indefinite extent a screw nut F is placed upon the out end of the rod, by which means the expansion of 60 the sash is regulated.

Now I am aware that the strip B with the springs behind it is not new, and I am also aware that the said strip has been drawn in by means of a lever and connection between the strip and lever. These, therefore, I do not claim as such, but

What I claim is—

The lever H, the adjustable connection G, and the springs J and E and bolt I or their 75 equivalents, in combination with the yielding strip B, for the purpose specified.

NELSON BARNUM.
